Des. 210,828
Patented Apr. 23, 1968

210,828

DOUBLE LAUNDRY TUB

Bernard E. Mustee, Fairview Park, Ohio, assignor to

E. L. Mustee & Sons, Inc.

Filed Sept. 15, 1966, Ser. No. 3,885

Term of patent 14 years

(Cl. D23—62)

Fig. 1

Fig. 2

Fig. 3

The rear and bottom are plain.

I claim:

The ornamental design for a double laundry tub, as shown and described.
